(57) **CLAIM**

The ornamental design for a wheel flare for a sport utility vehicle, as shown and described.

DESCRIPTION

FIG. 1 is a perspective view of a wheel flare for a sport utility vehicle, showing our new design, it being understood that broken line disclosure of the car is for illustrative purposes and forms no part of the claimed design;

FIG. 2 is an enlarged right side view thereof;

FIG. 3 is a front elevational view of FIG. 2;

FIG. 4 is a rear elevational view of FIG. 2;

FIG. 5 is a top plan view of FIG. 2;

FIG. 6 is a left side elevational view of FIG. 2;

FIG. 7 is a bottom plan view of FIG. 2;

FIG. 8 is a section view taken along line 8—8 in FIG. 6;

FIG. 9 is a right side elevational view of a second embodiment of a wheel flare for a sport utility vehicle, showing our new design;

FIG. 10 is a front elevational view of FIG. 9;

FIG. 11 is a rear elevational view of FIG. 9;

FIG. 12 is a top plan view of FIG. 9;

FIG. 13 is a left side elevational view of FIG. 9;

FIG. 14 is a bottom plan view of FIG. 9; and,

FIG. 15 is a section view taken along 15—15 in FIG. 13.
